United States Patent Office.

JOHN BRYCE, OF EAST BIRMINGHAM, PENNSYLVANIA.

Design No. 3,716, dated October 19, 1869.

DESIGN FOR ORNAMENTING GLASS-WARE.

The Schedule referred to in these Letters Patent and making part of the same.

To all whom it may concern:

Be it known that I, JOHN BRYCE, of East Birmingham, in the county of Allegheny, and State of Pennsylvania, have invented a new and useful Design for Glass-Ware; and I do hereby declare the following to be a full, clear, and exact description thereof, reference being had to the accompanying drawing, making a part of this specification, in which—

Figure 1 is a plan view of my improved design;

Figure 2 is a sectional view through $x-x$, fig. 1, illustrative of the raised and roughened structure of the leaves; and

Figure 3 is a sectional view through $x'-x'$, fig. 1, illustrative of the raised representation of the fruit or berries.

Like letters of reference indicate like parts in each.

My improved design consists in the raised representation, on the face of glass-ware, of a grape-vine, leaves, and fruit, the vine being striated, and the face of the leaves roughened.

The design is made on the article of glass-ware in *relievo*, by the use of properly-shaped cavities in the moulds.

The vine a is striated on its upper face, in imitation of the small lines or striations of the natural vine, as shown.

The fruit or berries c are also raised, so as to present an increased amount of reflecting-surface, and so add to the brilliancy of the design.

The leaves b are likewise raised, and the face of each leaf, between the raised skeleton and edges, is "roughened," as it is termed in the art.

This design I arrange by repeating it, if necessary, on and around the bowl of one or all the bowl-shaped articles of a set of glass-ware, and if arranged around a central knob, d , or a stem or foot, I use it with or without the raised ends e of bunches of grapes, and e' of grape leaves, the latter being roughened as before described, and both pointing radially out from such knob or stem, and arranged alternately with each other.

What I claim as my invention, and desire to secure by Letters Patent, is—

A design for glass-ware, consisting of striated vine a , fruit c , and roughened leaves b , the whole being made in *relievo*, and arranged substantially as shown.

In testimony whereof, I, the said JOHN BRYCE, have hereunto set my hand.

JOHN BRYCE.

Witnesses:

JOHN GLENN,
G. H. CHRISTY.
